DOUBLE IGNITION SYSTEM FOR INTERNAL COMBUSTION ENGINES

Luigi Torriani, Milan, Italy, assignor to Società Italiana Sfruttamento Brevetti Elettromeccanici, Milan, Italy

Application September 17, 1937, Serial No. 164,267
In Germany December 19, 1936

3 Claims. (Cl. 123—148)

This invention relates to a double ignition system for internal combustion engines.

Double ignition systems are already known wherein two commutator make and break devices are used together with switching means whereby the devices and circuits can be alternately put into operation.

There are also double ignition systems wherein the two circuits are governed by a single commutator make and break device and used alternately, separate switches being provided for closing and opening the circuit.

The object of the present invention is to obtain a device whereby a complete change over from one circuit to another can be effected by means of a single switch lever, and the invention consists essentially in the provision of a rotary cam which co-operates with two make and break contacts, one for each circuit, a switch lever being provided which, as it is turned, for switching one circuit on and the other off, simultaneously operates a cam whereby the make and break contact of the circuit to be used is thrown into operation and the other thrown out of operation.

Fig. 1 of the accompanying drawings represents a sectional view of the entire apparatus,

Fig. 2 is a detail view of this device,

Fig. 3 is a perspective view of a disc carrying the make and break contacts.

Fig. 4 is a perspective view seen from the opposite side of the disc, and

Fig. 5 is a diagram of the electric connections.

The device comprises a casing 1 wherein a rotary, permanent magnet 4 is housed together with an armature 30 and a sheet metal bundle 24 which forms the magnetic circuit. The casing is closed by a disc 11 which supports a shaft carrying outside the disc a cam 13 and inside the disc a gear wheel 31 through which and through a pinion 5 motion is transmitted to the cam 13 on the shaft 10 of the magnet 4. Pivotally mounted on the outside of the disc 11 are two spring-controlled members 15 and 15' which bear under the spring pressure against the cam 13 so as to be rocked by the latter for making and breaking two ignition circuits one of which is energized by the magnet 4 and the other by a battery 27 and an induction coil 25. The members 15 and 15' carry for this purpose platinized contacts 14 and 14' respectively which co-operate with corresponding rigid contacts connected to an insulating block 12 mounted on the disc 11. On the opposite side of the disc 11 there is a switch lever 18 which pivots by means of an annular cam 16 about a support which is coaxial with the cam 13. The members 15 and 15' are provided with fingers which project through aper-

tures in the disc 11 for engagement with the cam 16, the latter being shaped so that in each end position of the lever 18 one of the members 15 and 15' is permanently maintained in inoperative position. On a further lever arm connected to the cam 16 there is a contact member 17 which, as shown in Fig. 5, co-operates with contacts 21 and 22 for connecting either ignition circuits with the distributor 19 whereby the sparking plugs 20 are successively brought into the circuit, the distributor being synchronized in known manner with the cam 13. It will be seen from the diagram that a reversal of the lever 18 for changing over from one ignition circuit to the other, at the same time throws the make and break contact of the opposite circuit, out of operation.

There is a resistance 26 in the battery circuit and condensers 28 in both circuits. The arrows 23 indicate the path of the current in the magnet. The distributor 19 operates with sliding brushes 32.

I claim:

1. In a double ignition system for internal combustion engines, in combination, a rotary cam co-operating with two independent make and break contacts, one for each ignition circuit, a distributor common to both ignition circuits, a second cam co-operating with contacts for connecting either ignition circuit with said common distributor and adapted simultaneously to render inoperative one of said make and break contacts when the ignition circuit of the other contact is connected, and a single switch lever operative to actuate said second cam.

2. In a double ignition system for internal combustion engines, in combination, a rotary cam mounted on one side of a disc and co-operating with two independent make and break contacts, one for each ignition circuit, a distributor common to both ignition circuits, an annular cam in the other side of the disc which is connected to a lever arm carrying a contact member co-operating with contacts for connecting either ignition circuit with said common distributor and which is adapted to engage with fingers of said make and break contacts projecting through apertures in the disc so as simultaneously to render inoperative one of said make and break contacts when the ignition circuit of the other contact is connected, and a single switch lever operative to actuate said annular cam and pivoting by means of said cam about a support coaxial with the rotary cam.

3. Apparatus according to claim 2 wherein the disc closes a casing in which a magnet is housed.

LUIGI TORRIANI.
